DISPLAY CASE FOR CHAIN BRACELETS

William C. Boots, Rumford, R. I., assignor to
Foster Metal Products Incorporated, Attleboro,
Mass., a corporation of Massachusetts

Application May 20, 1953, Serial No. 25,116

Term of patent 14 years

(Cl. D80—5)

To all whom it may concern:

Be it known that I, William C. Boots, a citizen of the United States, residing at Rumford, in the county of Providence and State of Rhode Island, have invented a new, original, and ornamental Design for a Display Case for Chain Bracelets, of which the following is a specification, reference being had to the accompanying drawing forming a part thereof in which:

Figure 1 is a plan view of a display case for chain bracelets showing my new design.

Figure 2 is a sectional view on the line 2—2 of Figure 1.

The dominant features of my design reside in the portions shown in full lines.

I claim:

The ornamental design for a display case for chain bracelets, substantially as shown and described.
